UNITED STATES PATENT OFFICE.

WARREN McARTHUR, JR., OF CHICAGO, ILLINOIS, ASSIGNOR TO R. E. DIETZ COMPANY,
A CORPORATION OF NEW YORK.

TUBULAR LANTERN.

1,146,338.

Specification of Letters Patent. Patented July 13, 1915.

Application filed July 19, 1913. Serial No. 779,909.

To all whom it may concern:

Be it known that I, WARREN McARTHUR, JR., a citizen of the United States, residing at Chicago, in the county of Cook and State 5 of Illinois, have invented a new and useful Improvement in Tubular Lanterns, of which the following is a specification.

This invention relates to a burner structure for tubular lanterns in which the wick 10 tube is permanently secured in place on the oil pot, as distinguished from structures in which the wick tube forms part of a burner which is removably seated in a socket in the oil pot.

15 The object of this invention is to provide a simple, durable and compact structure by which the parts are securely held in position and the escape of oil from the wick tube to the outside of the lantern is prevented.

20 In the accompanying drawings: Figure 1 is an elevation of the oil pot and connecting parts of a tubular lantern embodying this improvement. Fig. 2 is a fragmentary top plan view of the same on an enlarged scale.

25 Fig. 3 is an elevation of the burner cone and globe plate. Fig. 4 is a vertical section of the upper part of the oil pot and the air chamber thereon on an enlarged scale. Fig. 5 is a detached sectional elevation of the wick tube 30 and connecting parts at right angles to Fig. 4. Fig. 6 is a detached elevation of the cup on which the wick tube is supported at right angles to Fig. 5. Fig. 7 is a fragmentary elevation of the air chamber. Fig. 8 is a

35 fragmentary vertical section illustrating a modified connection of the cup with the bottom of the air chamber. Fig. 9 is a fragmentary vertical section showing a modified embodiment of the invention.

40 Like reference characters refer to like parts in the several figures.

Referring to Figs. 1-7, A represents the oil pot having a peripheral wall 10 and an oval annular top plate 11 terminating in an 45 upstanding collar 12. The peripheral wall and the top plate are preferably formed in one piece in the usual manner. 13 represents an annular diaphragm or transverse

plate which is secured within the upper portion of the peripheral wall by soldering and 50 which forms the top of the oil pot and the bottom of the air chamber B on the same, the top of the air chamber being formed by the oval top plate 11. 14 represents the tubes which are secured to the oval top plate 55 in the usual manner.

15 represents a cup-shaped guard which is secured in the central opening of the diaphragm 13, and 16 represents the wick tube which is secured at its lower end in the bottom of this cup. 17 represents the wick-raiser shaft which is arranged in notches 18 in the upper edge of this cup and in notches 19 in the collar 12. The opening in the top plate 11 which is surrounded by the collar 60 12 is covered by a perforated plate 20 which is seated with its downwardly turned marginal portion upon the collar 12 and which 65 may be permanently secured thereto. The wick tube extends upwardly through an oblong opening 21 in the plate 20 and the latter is preferably provided in this opening with lips 210, Figs. 2, 4 and 9, which bear against the wick tube. The opening 21 is somewhat larger than the wick tube so that 70 any oil which may escape from the upper end of the wick tube can flow downwardly along the tube and into the cup from which such oil can return into the wick tube through an opening 22 formed near the 75 lower end of the wick tube. The lips 210 of the perforated plate are preferably bent downwardly, as indicated in Figs. 4 and 9, to prevent oil which flows down on the outer side of the wick tube from passing outwardly upon the perforated plate.

23 represents the wick raiser or ratchet wheels and 24 represents the upright slots formed in the wick tube for the same. Any oil which escapes through these slots passes 90 into the cup and from the latter through the opening 22 back into the wick tube and the oil pot. The cup prevents any oil which escapes from the wick tube from passing into the air chamber and forms an oil guard 95 located between the air chamber and the

drainage opening 22 through which the oil is returned to the oil pot. If any oil should flow along the wick-raiser shaft it is stripped from the shaft by contact with the 5 upper portion of the cup and caused to flow down on the inner side of the cup.

The cup may be secured to the diaphragm 13 by soldering or by clenching the bottom of the cup against the underside of the diaphragm, as represented in Fig. 8.

25 represents the burner cone which is separate from the wick tube and is preferably secured to the globe plate 26 in a well known manner.

15 In the construction represented in Fig. 9, the air chamber D is separate from the oil pot and is of cup shape, having a bottom 26 resting upon the top plate 27 of the oil pot. The bottom 26 and the top plate 27 are provided with coinciding central openings in 20 which the cup or guard 15 is secured. The perforated top plate 28 through which the wick tube projects is provided with an imperforate marginal portion 29 which forms the 25 top of the air chamber.

The drainage opening can be formed in the bottom of the cup instead of the wick tube, as represented at 30 in Fig. 9, but this is less desirable because when the opening is 30 formed in the wick tube there is less likelihood of oil being splashed from the oil pot into the cup by violent movements of the lantern.

I claim as my invention:

35 1. The combination with an oil pot and an air chamber upon the same, of a wick tube permanently connected with said pot, a guard which surrounds the wick tube within the air chamber and is permanently 40 connected with said oil pot and said wick tube, and an oil drainage opening arranged inside of said guard and leading from the lower portion of the air chamber to the oil pot.

45 2. The combination with an oil pot and an air chamber upon the same, of a wick tube permanently connected with the oil pot, a guard surrounding the wick tube and extending upwardly from the bottom of said 50 air chamber, and a drainage opening formed in the lower portion of said wick tube within said guard.

3. The combination with an oil pot and an air chamber upon the same having a central opening in its bottom, of a cup-shaped guard permanently secured in said opening, and a wick tube permanently secured in the bottom of said guard.

4. The combination with an oil pot and 60 an air chamber upon the same having a central opening in its bottom, of a cup-shaped guard permanently secured in said opening, a wick tube permanently secured in the bot-

tom of said guard, and a drainage opening inside of said guard.

5. The combination with an oil pot having a raised top plate which extends upwardly from the outer marginal portion of the oil pot and forms the top of an air chamber, tubes connected with said top, a diaphragm secured within the oil pot and extending substantially from the peripheral portion of the oil pot and forming the bottom of said air chamber, and a wick tube 70 permanently connected with the oil pot and 75 extending upwardly through said air chamber.

6. The combination with an oil pot having a raised top plate which forms the top of an air chamber, tubes connected with said top, 80 a diaphragm secured within the oil pot and forming the bottom of said air chamber, a cup-shaped guard secured within the air chamber in a central opening in said diaphragm, and a wick tube permanently secured to the bottom of said guard.

7. The combination with an oil pot having a raised top plate which forms the top of an air chamber, tubes connected with said top, 90 a diaphragm secured within the oil pot and forming the bottom of said air chamber, a wick tube permanently connected with said oil pot and extending upwardly through said air chamber, and a separate piece 95 perforated top plate applied to said air chamber and surrounding said wick tube.

8. The combination with an oil pot, an air chamber above the same, a guard extending upwardly from the bottom of said air chamber and provided in its upper edge with 100 notches for the reception of a wick-raiser shaft, a wick tube permanently connected with said oil pot, and a wick-raiser shaft arranged in said notches.

9. The combination with an oil pot having 105 a raised top plate which forms the top of an air chamber and which terminates in an up-standing collar having notches for the reception of a wick-raiser shaft, a diaphragm secured within the oil pot and forming the 110 bottom of said air chamber, a guard extending upwardly from said bottom and having notches in its upper edge for the reception of said wick-raiser shaft, a wick tube permanently connected with the oil pot, and a 115 wick-raiser shaft arranged in said notches.

10. The combination of an oil pot, an air chamber above the same having a central opening in its top, a wick tube permanently connected with said oil pot and extending 120 through said opening in the top of the air chamber, and a perforated plate closing the opening in the top of said air chamber and having an opening through which the wick tube projects.

11. The combination of an oil pot, an air

chamber above the same having a central opening in its top, a wick tube permanently connected with said oil pot and extending through said opening in the top of the air chamber, and a perforated plate closing the opening in the top of said air chamber and having an opening through which the wick tube projects, said plate being provided in

said opening with lips which bear against said wick tube.

Witness my hand, this 15th day of July, 1913.

WARREN McARTHUR, JR.
